UNITED STATES PATENT OFFICE.

JOSEPH E. CAMP, OF WASHINGTON, ILLINOIS, ASSIGNOR TO CAMP BROS. & CO., OF METAMORA, ILLINOIS, A CORPORATION OF ILLINOIS.

HYDRAULIC MOTOR FOR WAGON-DUMPS.

No. 909,280.

Specification of Letters Patent.

Patented Jan. 12, 1909.

Application filed April 27, 1906. Serial No. 314,012.

To all whom it may concern:

Be it known that I, JOSEPH E. CAMP, citizen of the United States, residing at Washington, in the county of Tazewell and State of Illinois, have invented certain new and useful Improvements in Hydraulic Motors for Wagon-Dumps; and I do hereby declare that the following is a full, clear, and exact description of the invention, which will enable others skilled in the art to which it appertains to make and use the same.

This invention pertains to improvements in wagon dumps, and relates more particularly to a dump in which hydraulic means is used for raising the wagon.

The object of the present invention is to provide an hydraulic cylinder whose piston is adapted to descend for the purpose of raising the wagon through overhead ropes.

20 A further object is to provide an hydraulic device for raising a wagon, the piston of which is adapted to descend instead of ascend as in other forms of this machine forming the subject of previous applications of mine in this line of devices.

25 A further object of the invention is to provide an overhead derrick beneath which the loaded wagon is driven, said derrick having at one end an hydraulic means for elevating the wagon through ropes depending from such derrick.

A further object lies in the employment of a valve carried by the piston and opened automatically at the time the piston reaches 30 the end of its travel so as to automatically relieve the pressure which operates said piston.

The invention also relates to certain details of construction and arrangement of 40 parts as will be pointed out in the following description and in the accompanying claims.

In the appended drawing, Figure 1 is a perspective view of my invention. Fig. 2 is a 45 vertical section of a cylinder and fluid tank and the connection therebetween. Fig. 3 is a vertical section of a portion of the lower end of the cylinder showing a relief valve in the piston also shown within the cylinder. Fig. 50 Fig. 3.

A indicates two vertical frames of a derrick which carry at their tops a horizontal beam B having two pulleys C suspended therefrom by suitable members such as D.

55 At one end of the derrick is a platform E hav-

ing mounted thereon a vertical cylinder F having therein a piston and piston rod G and H respectively, Fig. 2. Immediately above the cylinder beneath the beam B of the derrick are suspended two pulleys J over each of which runs a rope K one of which extends to and over the adjacent pulley C before described. The other rope extends to and over the remaining pulley C. The ends of the ropes just above the cylinder are suitably attached to the piston rod while the ends which are suspended from the pulleys C are each provided with a loop for engaging the hubs of the wagon wheels; the entire device as described being readily portable in the same manner as other apparatus of its class.

At M is a fluid tank preferably above the cylinder. The bottom of said tank is connected through a pipe N with a pump O carried on the platform E. Said pump is mounted on members P secured to the platform and is adapted to oscillate between said members to accommodate itself to the movements of its piston rod Q operated by an eccentric S on a shaft T; said piston rod having an eccentric strap R which surrounds said eccentric. The shaft T is carried in bearings U on the platform and is driven from the elevator (not shown) through a belt V and pulley W. I have not shown details of the pump since 85 a device of this kind is well understood. Connected into the pump is one end of a pipe 2 also connected at its other end into the top of the cylinder F as shown in Fig. 2. A pipe 3 connects the bottom of the cylinder with the top of the tank M and a short pipe at 4 connects said pipe 3 with the top of the cylinder as well; there being a cut-off valve 5 in said pipe 4 operated by means of a lever 6 and a pull-rod 7.

In Fig. 3 the piston G of the cylinder F is illustrated in part section in order to show a relief valve G¹ the stem G² of which occupies a bore G³ in said piston. Said bore terminates in the upper surface of the piston in a conical seat G⁴ in which the head G⁵ is adapted to seat. The valve thus constituted is provided with a pin at G⁶, and between said pin and the under surface of the piston is a spring G⁷ for normally holding the said head G⁵ in its said seat G⁴.

In the operation of raising the wagon the piston, in order to raise the loops L, must descend and in order to cause this action a fluid, preferably oil, is pumped into the top

of the cylinder through the pipe 2 by means of the pump O the supply being received from the tank M through the pipe N said tank being part of the pipe system and serving to hold the oil displaced by the piston-rod H, it being obvious that the cylinder holds less oil when the piston-rod is positioned therein than when it is outside.

A check valve N' is placed in the latter pipe so that the oil can only pass in one direction, that is, from the tank M to the pump. A similar valve 8 is also placed in the pipe 2 so that pressure can pass toward the cylinder F but not in the contrary direction. It will be understood that the pressure within the cylinder will force the piston down thus drawing upon the ropes K K the loops of which will be raised. In order to have the raising movement of the wagon under perfect control I provide the cut-off valve 5 and the pipe 3 hereinbefore described. Since by opening the said valve a passage will be opened from the top of the cylinder to the tank M the oil under pressure in the former will escape to said tank as it is forced into the cylinder by the pump. The amount of pressure admitted through the valve 5 will govern the rate of travel of the piston and the wider said valve is opened the slower the piston will travel until a point is reached where the weight of the wagon is balanced by the pressure and the piston is held stationary, the balance of pressure returning to the pump. If, however, the valve be opened wide the oil in the cylinder will be allowed to pass therethrough to the tank M by the raising movement of the piston due to the weight of the wagon suspended from the ropes K K. In this way the wagon is lowered after being relieved of its load, the piston remaining at the top of the cylinder as long as the valve is left open since if the pump is continually in motion the oil entering the cylinder will pass at once through said valve to the said tank. My device is automatic in its action in that after the wagon has been raised to its full height, *i. e.* when the piston is at the bottom of the cylinder the oil being continuously entered to the latter is given a path back to the tank M from which it is drawn. The means for admitting of this action is the valve G' hereinbefore described. It will be noted that the stem of this valve extends some distance below the lower face of the piston and as the latter approaches the bottom of the cylinder the said stem contacts with the said bottom as the piston continues to descend, thereby carrying its conical seat G⁴ away from beneath the said valve. The oil is thus given a small outlet and passes down through the bore G³ and thence into the pipe 3 as indicated by the arrow in Fig. 3. It is to be noted that the stem of the valve is in the form of a cross there being spaces between the limbs thereof through which the oil can

pass. It is evident that the oil in being put under pressure will force the piston down until the valve G' is opened as described at which time the pressure is relieved just enough to prevent overwork on the pump 70 and yet hold the piston stationary as long as it is desired that the wagon should remain in the raised position. Evidently the opening of the valve 5 at any time will allow speedy escape of the oil which may either pass to the 75 tank M or descend through the pipe 3 and enter the cylinder beneath the piston. It is quite evident that in order to let the piston rise oil must be allowed to enter beneath it from above the piston through the valve 5. 80 Then after the piston has reached the top of the cylinder and the latter is full of oil below said piston, the pipe 3 being also full, the oil still entering on top of the piston from the pump will pass the valve 5 and reach the tank 85 M. When the valve 5 is closed the piston is made to descend as described, the oil thereunder then passing to said tank M.

Means may be employed, of course, for stopping the pump, if desired, instead of permitting it to run continuously but in using the apparatus as described and shown the operator uses but the one valve 5. The operation is, therefore, very simple the device being perfectly automatic.

In other devices of this character the piston is forced upward by pressure to raise a wagon but in the present case the piston is forced downward to accomplish the same end. Further than this I have provided the 100 automatic relief valve in the piston which I regard as new in devices of this character. The arrangement is quite simple in construction by reason of having the automatic relief valve and it is, of course, possible to 105 use said valve on the pistons which move upward as well by simply reversing its position in said piston.

I am apprised of a hoisting device wherein a vertical cylinder is used which has pressure 110 entered at its top to force the piston down, the latter having connection with a suitable raising tackle. But in this patent the pressure is relieved through the same pipe by which it is entered to the cylinder. Moreover, the device is of such a nature that it cannot be transported from place to place as is necessary in a wagon dump. The construction in the present application is compact and can therefore be readily moved 115 from place to place if desired.

I claim—

1. In an apparatus of the class described, a fluid pressure cylinder and its piston and piston-rod, in combination with a system for holding fluid, including a continuously acting pump for producing a continuous and uniform pressure at all times, means for continuously operating said pump to produce said uniform pressure, a fluid conduit connecting 130

the pump with one end of the cylinder, a fluid receiving vessel forming part of said conduit, a check valve in said conduit to give flow only toward the pump, a second fluid conduit connected to the first outside the pump between the check valve and the cylinder and connected with the latter at the end opposite that to which the first conduit is connected, a manually operated valve in 10 said second fluid conduit, a third conduit connecting the pump with that end of the cylinder to which the second conduit is connected and by a route entirely separate from the first and second conduits, and a check 15 valve in said third conduit.

2. In a hydraulic jack, a cylinder and its piston, a pump, a fluid receiving vessel, a conduit connecting the pump and vessel, a check valve therein, a conduit connected 20 with the vessel and also with the bottom of the cylinder, a conduit connecting the last named conduit with the top of the cylinder, a manually operated valve therein, a conduit connecting the pump with the top of the 25 cylinder, and a check valve therein.

3. In a hydraulic jack, a cylinder and its piston, a pump, a fluid receiving vessel, a conduit connecting the pump and vessel, a check valve therein, a conduit connected 30 with the vessel and also with the bottom of the cylinder, a conduit connecting the last named conduit with the top of the cylinder, a manually operated valve therein, a conduit connecting the pump with the top of the cylinder, a check valve therein, and a valve in 35 the piston of said cylinder for the purposes set forth.

4. A cylinder and its piston, a device for continuously pumping fluid, a pipe connecting it with the top of the cylinder, a check valve in the pipe for permitting passage of fluid only in the direction of the cylinder, a fluid receiving vessel, a pipe connecting the fluid vessel with the opposite side of the 45 pump, a check-valve therein for permitting passage of fluid only in the direction of the pump whereby the fluid is drawn from said

vessel and entered into the cylinder upon the piston, a valve in the said piston adapted to contact with the bottom of the cylinder and 50 automatically open against the pressure of fluid behind it to relieve said pressure when the piston has reached its lowest position, a pipe connecting the bottom of the cylinder with the said fluid vessel whereby the pressure 55 passed through said valve is returned to said vessel, the escaping fluid relieving part of the pressure of the pump, the remaining pressure holding the piston depressed.

5. A cylinder and its piston a device for continuously pumping fluid, a pipe connecting it with the top of the cylinder, a check valve in the pipe for permitting passage of fluid to the cylinder but not in the opposite direction, a fluid receiving vessel, a pipe connecting the fluid vessel with the opposite side of the pump, a check valve therein for permitting passage of fluid only in the direction of the pump whereby the fluid is drawn from said vessel and entered into the 70 cylinder upon the piston, a valve in the said piston adapted to connect with the bottom of the cylinder and automatically open against the pressure of fluid behind it to relieve said pressure when the piston has 75 reached its lowest position, a pipe connecting the bottom of the cylinder with the said fluid vessel whereby the pressure passed through said automatic valve is returned to said vessel, the escaping fluid relieving part of the 80 pressure of the pump, the remaining pressure holding the piston depressed, a pipe connecting the top of the cylinder with the pressure-relief pipe and a valve therein, the opening of which permits the discharge of the 85 fluid from above the piston to the bottom of the cylinder beneath said piston substantially as set forth.

In testimony whereof I affix my signature, in presence of two witnesses.
